UNITED STATES PATENT OFFICE

100,679

DESIGN FOR AN AUTOMOBILE TRAILER BODY

Ace H. Alexander, Hollywood, Calif.

Application March 24, 1936, Serial No. 61,759

Term of patent 7 years

To all whom it may concern:

Be it known that I, Ace H. Alexander, a citizen of the United States, residing at Hollywood, in the county of Los Angeles and State of California, have invented a new, original, and ornamental Design for an Automatic Trailer Body, of which the following is a specification, reference being had to the accompanying drawing, forming part thereof.

Fig. 1 is a side elevational view of an automobile trailer body showing my new design.

Fig. 2 is a top plan view.

Fig. 3 is a front elevational view.

I claim:

The ornamental design for an automobile trailer body, as shown.

ACE H. ALEXANDER.
